UNITED STATES PATENT OFFICE.

JAMES C. LEITCH, OF LOS ANGELES, CALIFORNIA.

ELECTRIC WATER-HEATER.

1,210,086.

Specification of Letters Patent. Patented Dec. 26, 1916.

Application filed July 6, 1915. Serial No. 38,042.

To all whom it may concern:

Be it known that I, JAMES C. LEITCH, a citizen of the United States, residing at Los Angeles, in the county of Los Angeles and State of California, have invented new and useful Improvements in Electric Water-Heaters, of which the following is a specification.

My invention relates to electric heaters 10 and more particularly to that class of heaters known as immersion heaters.

It is an object of my invention to provide an electric heater which is portable and may be handled while electrically connected, 15 without danger to the operator.

Another object of my invention is to provide an electric heater for liquids which depends upon the conductive qualities of the liquid in which it is immersed to complete 20 the electric circuit, so that there will be no heat generated within the heating elements when the heater is withdrawn from the liquid.

Another object is to provide an immersion 25 electric heater which embodies a spiral or helical inner conductor and an outer conducting helix insulated from the inner helix and forming spiral openings in the helices to permit the free circulation of the liquid 30 to and from the opposite sides of the helices.

It is a further object to provide a liquid 35 heater of the class described in which the heating element will be entirely exposed to the liquid and will at the same time be so constructed that a short circuit is not likely to occur due to foreign substances connecting the two poles of the heating element.

My invention is illustrated in the accompanying drawings in which:

40 Figure 1 is a perspective view illustrating the application of my invention as applied in heating liquid. Fig. 2 is a view of the heater in side elevation. Fig. 3 is a view in vertical section of a modification as seen on the line 3—3 of Fig. 2 and shows the outer spiral element and the inner spiral element as being wound in opposite directions. Fig. 4 is a section in plan on the lines 4—4 of Fig. 2.

45 More specifically, 10 is a screw plug which consists of the dielectric body member 11 mounted within the end of a metallic threaded sleeve member 14 adapted to engage complementary threads within the 50 socket 15 through which electric current is supplied to the contact member 12 and the

screw member 14 from electrical supply conduits 16 and 17. The lower end of body member 11 is enlarged as shown at 18 and has secured, by screw 19, to the outer periphery thereof, the end 20 of a helically wound conducting member 21; the opposite end 22 of which is secured to the outer circumference of an insulating base member 24 by a screw 23. Secured to the inner face 25 of the base 24 by a screw 26, is the end 27 of an inner helically wound conducting member 28 which projects into a counterbore 29 in the body member 11; end 30 of said conducting member being secured to 70 the contact member 12 by a screw 31.

The conducting member 21 is preferably formed of a ribbon of sheet metal with coils of equal diameter so as to conform to a cylinder; the coils being of a width greatly 75 in excess of the width of the spaces therebetween, but which spaces are sufficiently wide to permit the ready flow of liquid therethrough. The coil 28 is also preferably formed of a ribbon of sheet metal of a narrower width than the ribbon of which the coil 21 is formed and is wound to form a number of coils of equal diameter having broad outer faces extending concentric with and parallel to the inner faces of the coil 21, 80 and spaced therefrom to form a gap.

The coils 21 and 28 being insulated from each other by the end members 11 and 24, no current can pass therethrough when they are connected to a source of electrical supply, unless the coils be submerged in a liquid. By this arrangement, the device will operate to perform its heating function only when immersed, and will thereby permit its 95 being handled without danger of shock when not submerged; immersion of the device in a liquid operating to complete a circuit through the coils and withdrawing it from the liquid acting to break the flow of current through the coils.

100 By arranging the coil 28 within the coil 21 and forming the spaces between the coils of the latter, sufficiently narrow to prevent the ready introduction of objects therethrough, the inner coil is housed so as to obviate danger of accidental electrical connection of the coils.

In the operation of the invention, the plug 10 is positioned within the socket 15 and electrical current switched thereto. On 110 immersing the heating element in a liquid, as shown in Fig. 1, the liquid will operate

- as a conductor to complete electrical connection between the coils 21 and 28. The flow of current through the device will then be as follows: from socket 15 through the contact 5 member 12 to the inner coil 28, thence through the liquid to the coil 21, from whence it returns through the conducting member 32 secured to the upper end of the coil 21 by a screw 33 and completing connection with the socket 10 15 through the threaded sleeve 14. The current passing through the liquid operates to heat same. When the desired temperature of the liquid has been obtained, the device is withdrawn therefrom, thereby automatically breaking the flow of current through 15 the coils.

What I claim is:

1. In an immersion electric heating device, the combination of an inner helical electrode 20 and an outer helical electrode concentric with said inner electrode and dielectrically mounted therefrom, the space intervening between the convolutions of the material from which the electrodes are formed being 25 open and less than the width of said material between the spaces.
2. In an immersion electric heating device, the combination of an inner helical electrode, an outer helical electrode concentric with 30 said inner electrode, an electrical contact plug secured to one end of each of said electrodes, and a dielectric base secured to the opposite ends of said electrodes, said inner and outer electrodes being composed of metallic ribbon, the width of which is greater 35 than the space between the convolutions thereof, the spaces between said convolutions being open.
3. In an immersion electric heating device, 40 the combination of an inner electrode of helical form, an outer electrode of the same form encompassing said inner electrode and spaced therefrom, the spaces between the convolutions of said helices being open, electrical connections secured to one end of each 45 of said electrodes, and an insulating base securing the opposite ends of the electrodes.

4. In an electric heating device, the combination of an inner cylindrical electrode and an outer cylindrical electrode encompassing and insulated from the inner electrode, said cylindrical electrodes being formed with a helical opening extending the length thereof, and means whereby the inner and outer electrodes may be electrically 55 connected.

5. A water heating device comprising an inner conducting helix and an outer electric conducting helix encircling the inner helix concentric therewith and insulated therefrom, having the spaces between its coils open to permit the passage of fluid there-through.

6. A water heating device comprising an inner conducting helix having the spaces between its coils open, and an outer electric conducting helix encircling the inner helix concentric therewith and insulated therefrom, having the spaces between its coils open to permit the passage of fluid there-through.

7. A water heating device comprising an inner conducting helix and an outer electric conducting helix encircling the inner helix concentric therewith and insulated therefrom, having the spaces between its coils open to permit the passage of fluid there-through, said helices having their spirals of different widths.

8. An electric liquid heating device comprising a central helical conductor and an outer helical conductor encircling the inner conductor concentric therewith and insulated therefrom, having spaces between its coils open to permit the flow of liquid there-through, the widths of the coils of the outer helix being greater than the widths of the coils of the inner helix to position the spaces between the coils of the helices out of alignment with each other.

In testimony whereof I have signed my name to this specification.

JAMES C. LEITCH.
